UNITED STATES PATENT OFFICE

GULDBRAND GULDBRANDSEN, OF LOUISVILLE, KENTUCKY, ASSIGNOR TO E. AND T. FAIRBANKS AND COMPANY, OF ST. JOHNSBURY, VERMONT, A CORPORATION OF VERMONT

LAUNDRY-BAG SCALE

Application filed July 19, 1927. Serial No. 206,846.

This invention relates to weighing machines and more particularly to a weighing machine especially adapted for use in laundries.

5 In commercial laundry work, it has been the practice to place a definite quantity of goods by weight into a net bag and then washing the goods while still in the bag. This mode of washing substantially eliminates the 10 wear and tear on the goods caused by the action of the rotary power driven washing machine, the net bag bearing the brunt of the damage heretofore inflicted upon the goods by the friction incident to the mechanical washing 15 processes. It is quite essential that an accurate check on the weight of the goods be maintained, for it has been found by experience that when too great a quantity of goods had been placed in a bag, the washing 20 process was not satisfactorily accomplished and too small a quantity of goods is, of course, an economic loss to the laundry. It is accordingly an object of this invention to provide 25 a weighing device to measure the desired quantity of goods to be placed in a bag and which will hold the mouth of the bag in open position to enable the operative to readily place therein the goods to be washed.

30 Another object of this invention is the provision of a laundry weighing wherein the mouth of the laundry bag is automatically closed to indicate that a sufficient quantity of goods to be washed had been deposited therein and to facilitate the removal of the bag 35 from its supports.

Other features of this invention, together with certain details of construction and combination of parts, will be discussed in the 40 specification and pointed out in the appended claims.

In the drawings:

Fig. 1 is a perspective view of my device with a bag in open position thereon, as indicated by the dotted lines;

Fig. 2 is a front elevational view showing the position of the parts of the device after the bag has received the desired quantity of goods, the closed bag being indicated by 50 the dotted lines; and

Fig. 3 is a side elevational view of my device.

In the illustrative device there is shown a base generally indicated by the reference numeral 1, which is formed of a casting, the rear portion of which has substantially the configuration of an isosceles triangle having sides 2 and a base formed by a cross-piece 3. The base 1 is extended forwardly from the extremities of the cross-piece 3 to form a pair 55 of feet 4 and 5 which are adapted to give greater stability to the device. The feet and crosspiece 3 have cast integrally therewith enlarged portions, or bosses, 6 and 7, respectively. The bosses have screw-threaded apertures for the reception of bolts 8 which rigidly hold substantially triangular standards, or fulcrum stands, 9 in upright position on the base. A reinforcing rib 10 extends vertically of each standard 9 and is adapted to 60 give greater strength thereto.

The upper extremities of the standards are bifurcated, as at 11, said bifurcations forming seats for V-shaped bearing members 12 which are retained in position by means of lugs 13. Pivotedly supported on the bearings 12 by means of knife edge pivots 14 is a U-shaped lever 15, the pivots being set into the lever during the casting thereof. The displacement of the pivots is prevented by 75 pins 16 placed across the extremities of the bifurcated standards.

To one extremity of the U-shaped lever 15 is rigidly attached an upright arm 17 having at its upper extremity a cross-piece 18 integrally cast therewith and at a slight angle thereto, the purpose of which will herein-after be explained. On the other extremity of lever 15 are formed the projections 19, in which projections is pivoted the arm 20 having a cross-piece 21 similar in construction to cross-piece 18. On the lower end of arm 20 is cast a boss which is grooved and forms with coverplate 24, fastened to the boss by means of screws 23, a slot which is adapted to act as a guide and holder for a dog 25 slidably held therein.

Rigidly fastened to lever 15 is an arcuate locking ratchet 26 which passes through an aperture 27 in the dog 25. A rod 28, the up-

per portion of which is bent to form an arcuate trip-arm 29, is held in an enlarged portion, or boss, 30 in foot 5 of base 1. The dog 25 cooperates with the trip arm 29 to unlock the arm 20.

5 Substantially centrally of the U-shaped lever 15 and extending rearwardly is rigidly attached a beam 31 upon which is adapted to slide a balance weight, or poise 32. The poise carries a pointer 33 which cooperates with a 10 beam face index 34 to indicate the net weight of the goods to be placed in the laundry bag. The poise may be retained in adjusted position by means of a set screw 35.

15 The sides 22 of the base meet in an enlarged portion, or boss, 36 to which is rigidly attached a trig stand 37 into which is set a trig loop 38. A shield 39 which is adapted to steady the laundry bag as it is being filled 20 is suitably attached to the U-shaped lever, as by means of screws 40.

In operation, a net bag is suspended from arms 17 and 20 and is held in position by being draped over cross-pieces 18 and 21. The 25 operative then fills the bag with the goods to be laundered, the quantity of goods to be put in being determined by the position of the poise. The weight of goods put into the bag is normally between six and twelve pounds 30 depending upon the practice in the particular laundry. When a sufficient amount of goods had been deposited in the bag, the U-shaped lever is, by the weight of the bag and goods, tipped downwardly, the dog 25 striking 35 the trip arm 29 which releases said dog from the locking ratchet 26 and allows the arm 20 to be drawn inwardly by the weight of the bag. This indicates to the operative that the bag contains a sufficient quantity of 40 goods and also allows an easy removal of the bag from the cross-pieces 18 and 21.

The cross-pieces 18 and 21 of arms 17 and 20, respectively, are set at an angle in order that, when the lever 15 is tipped by the weight 45 of the bag and contents, the device may be quickly overbalanced and the arm 20 released and drawn inwardly with despatch.

Upon the bag and contents being removed the parts are quickly restored to their normal 50 position through the action of the poise 32.

Having thus described my invention, what I claim as new and desire to secure by Letters Patent of the United States, is:

1. In a device of the character described, 55 a lever, means on said lever adapted to normally hold a bag open, and means actuated by said lever for releasing said holding means when a predetermined quantity of goods is deposited therein.

60 2. In a device of the character described, a U-shaped lever, means on said lever adapted to normally hold a bag open, said means comprising a plurality of arms, one of said arms being pivoted and means cooperating 65 with said pivoted arm to close said bag when

a predetermined quantity of goods is deposited therein.

3. In a device of the character described, a U-shaped lever having an arm at each extremity thereof, one of said arms being pivoted, and means on said lever cooperating with said pivoted arm to hold said arm in upright position. 70

4. In a device of the character described, a U-shaped lever having an arm at each extremity thereof, one of said arms being pivoted, means on said lever cooperating with said pivoted arm to hold said arm in upright position and means for tripping said holding means. 75

5. In a device of the character described, a U-shaped lever, an arm at each extremity thereof, one of said arms being pivoted, a guide on said pivoted arm, a dog slideable in said guide, and means cooperating with the dog to lock said pivoted arm. 80

6. In a device of the character described, a U-shaped lever, an arm at each extremity thereof, one of said arms being pivoted, a guide on said pivoted arm, a dog slideable in said guide, means cooperating with said dog to lock said pivoted member, said means comprising an arcuate ratchet member. 85

7. In a device of the character described, a U-shaped lever, an arm at each extremity thereof, one of said arms being pivoted, a guide on said pivoted arm, a boss having an aperture therein slideable in said guide, and means extending through said aperture adapted to cooperate with said boss to lock 90 said pivoted arm.

8. In a device of the character described, a U-shaped lever, having a plurality of arms thereon, one of said arms being pivoted, a guide on said pivoted arm, a dog slideable in 95 said guide, said dog having an aperture therein, means extending through said aperture adapted to coooperate with said dog to lock said pivoted arm, said means comprising an arcuate ratchet member. 100

9. In a device of the character described, a lever having plurality of arms thereon, one of said arms being pivoted, a guide on said pivoted arm, a dog slideable therein, ratchet means cooperating with said dog to lock said pivoted arm, and means for unlocking the same. 115

10. In a device of the character described, a base, a plurality of standards mounted thereon, a lever pivoted on said standards, a beam on said lever, a poise on said beam, and means on said lever for holding a bag in open position, said means comprising a plurality of arms, one of said arms being pivoted. 120

11. In a device of the character described, a base, a plurality of fulcrum stands attached thereto, a lever pivoted on said stands, a beam on said lever, a poise cooperating with said beam means on said lever for holding 130

a bag open and means for automatically closing the bag.

12. In a device of the character described, a base, a plurality of fulcrum stands mounted thereon, a U-shaped lever pivoted on said stands, means on said lever adapted to hold a bag open, means for automatically closing said bag, a beam on said lever and a poise adjustable along said beam.

10 13. In a device of the character described, a base, a plurality of fulcrum stands mounted thereon, said stands having a lever pivoted thereon, a beam on said lever having a poise adjustable thereon, means on said lever 15 adapted to hold a bag open, said means comprising a plurality of arms, one of said arms being pivoted and normally locked and means for releasing said pivoted arm.

14. In a device of the character described, 20 a base, a plurality of fulcrum stands mounted thereon, said stands having bifurcations in the upper extremities thereof, a lever pivoted in said bifurcations, said lever having a beam thereon, a poise adjustable along 25 said beam, means on said lever for holding a bag open, said means comprising a plurality of arms, one of said arms being pivoted and normally locked and means for unlocking said pivoted arm.

30 In testimony whereof I have signed my name to this specification.

GULDBRAND GULDBRANDSEN.
